(57) **CLAIM**

The ornamental design for a cover for an opening in a beverage lid, as shown and described herein.

DESCRIPTION

FIG. 1 is a perspective top view of a new design for a cover for an opening in a beverage lid, according to one embodiment of our new design;

FIG. 2 is a perspective bottom view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective top view of a new design for a cover for an opening in a beverage lid, according to a second embodiment of our new design;

FIG. 10 is a perspective bottom view thereof;

FIG. 11 is a front view thereof;

FIG. 12 is a back view thereof;

FIG. 13 is a left side view thereof;

FIG. 14 is a right side view thereof;

FIG. 15 is a top view thereof; and,

FIG. 16 is a bottom view thereof.

FIGS. 1-8 and FIGS. 9-16 depict the same embodiment of the cover for an opening in a beverage. FIGS. 1-8 include shading lines not included in FIGS. 9-16 which represent an opaque surface and from no part of the claimed design.

1 Claim, 6 Drawing Sheets
